UNITED STATES PATENT OFFICE

166,857

COMBINED WALLET AND PURSE

Frank X. Hiltenbrand, Ridgefield, N. J.

Application January 24, 1952, Serial No. 18,201

Term of patent 3½ years

(Cl. D87—3)

To all whom it may concern:

Be it known that I, Frank X. Hiltenbrand, a citizen of the United States of America, residing in Ridgefield, county of Bergen, and State of New Jersey, have invented a new, original, and ornamental Design for a Combined Wallet and Purse, of which the following is a specification, reference being had to the accompanying drawing, forming part thereof, wherein,

The rear of the article is substantially the same in appearance as the front shown, except for the omission of the shield-like trim and the tab closure.

I claim:

The ornamental design for a combined wallet and purse, substantially as shown, and described.

FRANK X. HILTENBRAND.
